UNITED STATES PATENT OFFICE.

KARL WESSEL, OF ST. PAUL, MINNESOTA.

HEAT-INSULATING MATERIAL.

1,295,654.

Specification of Letters Patent. Patented Feb. 25, 1919.

No Drawing.

Application filed September 4, 1917. Serial No. 189,492.

To all whom it may concern:

Be it known that I, KARL WESSEL, a citizen of the United States, residing at St. Paul, in the county of Ramsey and State 5 of Minnesota, have invented certain new and useful Improvements in Heat-Insulating Material; and I do hereby declare the following to be a full, clear, and exact description of the invention, such as will enable 10 others skilled in the art to which it appertains to make and use the same.

My invention has for its object to provide a highly efficient and inexpensive heat insulating material which, when made in 15 sheets of proper thickness, is especially adapted for use in insulating walls of refrigerators, refrigerator cars, and dwellings. This improved heat insulating material is made, preferably of about equal parts of 20 flax, cereal straw and peat, together with enough water to float the same, put into a beater, such as used in making pulp and thereby thoroughly commingled and beaten up and reduced approximately to what is 25 known as "half stock". The peat will be reduced more rapidly than the flax and cereal straw and will act more or less as a binder to the more fibrous particles of the flax and straw, while the fibers of the 30 flax and straw, although short, give strength to the material, or sheet formed therefrom. The peat can be advantageously introduced after the flax and straw have been well beaten up and intercommingled. In fact, 35 this late introduction of the peat is desirable to avoid reducing the peat to too fine consistency.

The commingled materials, while soaked and containing a large amount of water, 40 will be suitably spread out, and the water pressed therefrom and the sheet dried. This may be done in different ways, but commercially, I propose to make this insulating material in a machine especially designed for 45 a continuous and rapid formation of such insulating sheets and which machine is made

the subject matter of a companion application filed of date, September 4, 1917, under S. N. 189,493, and entitled "Machine for making insulating sheets".

These insulating sheets, when dried, will have considerable flexibility and strength, and at the same time, will be light in weight. Moreover, such sheets, because of the very large number of minute air cells or air 55 spaces therein, and because of the non-heat conducting quality of the substances, are very efficient as a heat insulator. All of the materials employed in the formation of the sheet are of comparatively low cost. The 60 cereal straw, which is preferably either wheat straw, rye straw or barley straw, is of much lower cost than the flax and the peat is of still less cost than the cereal straw. A limited amount of flax, however, 65 is desirable, because it adds to the strength of the material. The total cost of the several materials employed in the sheet is small, as compared with a similar material made entirely or nearly entirely from flax, 70 and moreover, has at least as good heat insulating qualities as the all-flax material.

What I claim is:

1. A heat insulating material made from flax, cereal straw and peat, intercommingled 75 and pressed into the form of a self-sustaining body.

2. A heat insulating sheet made from flax, cereal straw and peat intercommingled and reduced approximately to "half stock", and 80 pressed into a self-sustaining body.

3. A heat insulating sheet made from flax, cereal straw and peat in substantially equal parts, intercommingled and reduced substantially to "half stock" and pressed into a 85 self-sustaining body.

In testimony whereof I affix my signature in presence of two witnesses.

KARL WESSEL.

Witnesses:

CLARA DEMAREST,
BERNICE G. BAUMANN.
